CLAIM

The ornamental design for a water holding tub for sun tanning, as shown and described.

DESCRIPTION

FIG. 1 is a perspective view taken from the top, one end and one side of a water holding tub for sun tanning showing my new design;

FIG. 2 is an end elevational view thereof, the opposite end being the same as the end shown;

FIG. 3 is a side elevational view thereof, the opposite side being the same as the side shown;

FIG. 4 is a top plan view thereof; and,

FIG. 5 is a bottom plan view thereof.

FIG. 1

FIG. 2

*FIG. 3**FIG. 4**FIG. 5*
